NECKTIE SEWING APPARATUS

Victor M. Newman, New York, N. Y.

Application March 28, 1950, Serial No. 152,445

15 Claims. (Cl. 112—174)

1

This invention relates to the production of neckties and more particularly to a machine which is adapted to sew the necktie fabric and lining together. The application is a continuation in part of my prior application Serial No. 75,595, filed February 10, 1949.

In the above entitled prior application, it was pointed out that sewing machines having an elongated needle for stitching together the necktie lining and the edges of the necktie were known but that their use had been associated with some disadvantages. Such disadvantages included the non-adaptability of many prior machines toward accommodation of necktie fabrics which deviated from predetermined dimensions. Such machines would produce a distorted finished product which would be rejected as unusable. A further disadvantage was frequent breakage of the needle in that its guiding path was not properly formed. The instant invention is an improvement over the sewing apparatus disclosed in the above entitled application and further corrects or eliminates the above mentioned disadvantages.

The instant invention further produces an apparatus which does not distort or stretch the fabric in corrugating it preparatory to sewing the necktie elements together. This is accomplished by providing a collapsible stand comprising a plurality of lazy tong mechanisms and whereby the fabric, including the lining, becomes reduced in length through collapsing of the lazy tongs whereupon the elongated needle is actuated throughout the length of the necktie. Mounted on the lazy tongs are a plurality of aligned crimpler bars which determine the crimping or corrugation of the necktie elements preparatory to sewing them together. The crimpler bars are further provided with impaling needles for preventing undue movement of the necktie elements while they are being properly folded and sewn. The crimpler bars are further formed with mating recesses which jointly provide the needle guide path.

The invention further simulates hand operations in the sewing of neckties in that it affords an adjustment of the crimpler bars so that the lining is not stitched to the outer fabric along front and end portions thereof as is desirable in necktie production.

The sewing apparatus of the instant invention greatly simplifies the mechanism heretofore required in effecting what I consider superior results to those of prior constructions. Thus, the instant machine is simple to operate and far more economical to manufacture while nevertheless

2

providing superior action in the sewing of neckties.

The invention will be further understood from the following description and drawings in which:

Fig. 1 is a top plan view of a sewing machine constructed according to the instant invention.

Fig. 2 is an enlarged view of one end thereof illustrating the initial step in disposing a necktie lining in space.

Fig. 3 is a fragmentary view similar to Fig. 2 and illustrating the second step, that of disposing the necktie fabric in position.

Fig. 4 is a fragmentary view illustrating the operation of the crimpler bars.

Fig. 5 is a view similar to Fig. 4 but illustrating the succeeding step of collapsing the crimpler bars through the lazy tong mechanism.

Fig. 6 is a cross-sectional view along the lines 6—6 of Fig. 2.

Fig. 7 is a cross-sectional view along the lines 7—7 of Fig. 4.

Fig. 8 is a cross-sectional view along the lines 8—8 of Fig. 5.

Fig. 9 is a cross-sectional view along the lines 9—9 of Fig. 4.

Fig. 10 is a cross-sectional view along the lines 10—10 of Fig. 3.

Fig. 11 is a cross-sectional view along the lines 11—11 of Fig. 3.

Fig. 12 is a cross-sectional view along the lines 12—12 of Fig. 1.

The apparatus comprises a frame 20 having a top flange 21 and a center flange 22. Center flange 22 supports the lazy tong mechanism comprising the lazy tong arms 23, upper bars 24, and lower bars 24a. Lazy tong bars 24 and 24a are respectively disposed on both sides of the lazy tong arms and are interconnected as by rivets 25. Arms 23 are pivotally mounted on end pins 26, quarter point pins 26a, each of which is vertically movable in relation to the bars, while the central point of the lazy tong arms are pivotally mounted on the center rivets 27 which are connected to the bars. Spacers or washers 28 are disposed on the pins or rivets between the lazy tong arms for the usual purposes. It will be recognized from the foregoing that the lazy tongs per se comprise the usual elongated arms which, as illustrated in Figs. 1 and 2, are pivoted at their ends, center, and quarter points and cross other arms at such pivot points to accomplish the scissor-like action characteristic of lazy tong mechanisms.

The bars 24 and 24a have end flanges 29 which embrace the pins or rivets 26

so that the lazy tong arm ends may slide within the bars during extension or collapse.

Supported on the bars 24 are the crimper elements or bars which corrugate or crimp the fabric in cooperation with the collapse of the lazy tongs. Thus, stationary crimper 30 are connected as by screws 31 to the upper bars 24, the term "stationary" being employed to indicate absence of relative movement between them and the bars. Each crimper 30 has a triangular working surface terminating in an apex 32. It is this triangular face of the crimpers which effects the crimping action in cooperation with the opposing swingable crimper element or bar as will hereinafter be described.

As will be understood in the operation of this machine, it is necessary to form a needle guide path when the tie lining and fabric are corrugated or crimped. A portion of such needle guide path is provided by central recesses 35 formed in the apex 32 of crimper bar 30. Means are also provided in the present application to hold the lining and fabric securely in position when they are set in place, and impaling needles 36 serve this purpose. Needles 36 are formed with integral enlargements 37 for insuring retention of the fabric elements after they have been set in place.

The invention further contemplates adjustability of the crimper bars to accommodate neckties of various dimensions. For this purpose, the crimper bars are rendered transversely adjustable on the bars 24. Thus, crimper bar 30 is formed with a slot 38 through which operates the screw 31 for tightening the crimper bar 30 to bar 24 in various positions of transverse adjustment. The opposing or swingable crimper bar 40 has a working or surface element which is V-shaped so as to complement the triangular face of crimper bar 30. The extreme upper ends of the V arms of crimper bar 40 are provided with end recesses 41 which mate with recesses 35 when the lazy tongs are collapsed so as to form a continuous needle guide path. Crimper bar 40 is further formed with a central hole 42 for receiving impaling pin 36 when the crimper bars are engaged as illustrated in Fig. 7. It will be recognized from Fig. 2 that the crimper bars 30 are alternately provided with impaling needles 36 and recesses 42, the same arrangement being found in the crimper bars 40 so that the impaling needles are found on both sets of crimper bars.

Means are provided to render crimper bars 40 swingable in relation to bars 24 so that the crimper bars may become engaged when the bars 40 are swung into position over the bar 30. Thus, a central hinge comprising a fixed hinge arm 45 and a swingable hinge arm 46 are connected to bar 24 as by screw 47. A connecting link 48 having a longitudinal slot 49 adjustably connects crimper bar 40 to hinge arm 46 as by the screws 50 which may be tightened in slot 49 to provide transverse adjustment of crimper bar 40. It will be understood that when the crimper bars are engaged as illustrated in Fig. 7, it is necessary for both the recesses to align themselves properly and for the holes 42 to be in correct position for receiving the needles 36. The distance between the longitudinal center of the machine and either sets of recesses 35 or 41 must be the same because hinge pin 52 is at such center of the machine. Therefore, if crimper bar 30 is adjusted transversely as hereinabove described, it is necessary to do the same with crimper bar 40 by means of link 48. In this way,

the needle path recesses may be aligned, the impaling needle receiving holes 42 assuming the correct position at such time with relation to the impaling needles. In order that the approximate center of the fabric be securely held during the swinging engagement of the crimper bars, a central impaling needle 53 is provided as will be hereinafter made clear.

Referring to Fig. 1, most of the swingable crimper bars are interconnected by a manipulating member 55 comprising a handle and an elongated rod extending through substantially all of the swingable crimper bars 40. However, two end crimper bars 40 are not connected to manipulating member 55 so that they may be swingably actuated independently of the remaining swingable crimper bars as will be hereinafter more fully explained.

The invention is practiced as follows:

A tie lining L is first applied over the stationary crimper bars 30 as illustrated in Fig. 2, the impaling needles 36 penetrating the lining as it is thus applied. In conventional manufacture of neckties, it is desirable to run the thread through the end of lining L without sewing the necktie fabric thereto. Accordingly, the two end crimper bars are then swung over the stationary crimper bars as illustrated in Fig. 3 before the necktie fabric F is applied in position. In this way, the needle will enter the aligned needle guide path without sewing the fabric F to the lining at the end crimpers.

Thereafter, the necktie fabric F is placed in position over the lining L and so that the impaling needles 36 securely hold both edges of the necktie lining. It will be observed that central impaling needle 53 holds the center of the fabric down so as to prevent accidental displacement during operation of the crimper bars.

The operator then grasps manipulating member 55 and swings the crimper bars 40 over crimper bars 30, an action which folds the fabric F so that its edges become coincident over the lining L as illustrated in Fig. 4. It will be observed in Fig. 3 that the recesses 35 and 41 are disposed laterally and inwardly relative to the impaling needles 36 so that the aligned needle path is formed directly laterally inwardly of the coincident or superimposed edges of fabric F. Accordingly, when the sewing needle is caused to enter and traverse the aligned needle guide path, the superimposed longitudinal edges of the fabric F are then sewn to the approximate center of the lining L.

After the crimper bars have been engaged as illustrated in Fig. 4, the entire lazy tong mechanism is collapsed in order to crimp or corrugate the lining and superimposed fabric. This step is illustrated in Fig. 5 where the small end of the necktie fabric is bent back to illustrate the entry of the needle into the guide path.

Collapse of the lazy tong mechanism with the consequent crimping of the fabric and necktie lining and the formation of the aligned needle guide path is illustrated in Fig. 8. It will be observed that the recesses 35 and 41 mutually align to form a substantially continuous needle guide path, the continuity being interrupted by the thickness of the fabric and tie lining between adjacent crimper bars. It will be understood that the representation of the lining and fabric thickness are exaggerated in Fig. 8 so that in actual practice the space between adjacent portions of the needle guide path is minimal. When the needle N bearing the thread T is caused

to enter and traverse the needle guide path emerging therefrom as indicated in the broken lines of Fig. 8, the thread T will sew the longitudinal edges of the fabric F to the lining L through the crests thereof, the stitches being slip stitches and being spaced according to the width of the corrugations as will be evident. After this operation, the lazy tongs may again be extended and the sewn necktie fabric and lining removed from the apparatus.

In order to provide lengthwise adjustment of the lazy tong mechanism so as to accommodate neckties of various lengths, a bolt 60 (Fig. 1) may be screwed through a selected one of a series of openings 61 so that the end bar of bars 24 will be limited in its extending movement according to requirements. The opposite end bar is, of course, secured to the frame as illustrated in Fig. 2. Some of the bars are further provided with rollers 62 to facilitate the collapsing or extending action of the lazy tong mechanism.

It will be understood from the foregoing that a necktie sewing machine has been provided wherein a series of crimper bars are actuated by simple means so as to prepare a combined necktie lining and fabric for crimping and subsequent sewing for the purposes herein described. The mounting of such bars on the lazy tong mechanism insures proper sewing without distortion of the fabric. Other advantages will be apparent to those skilled in the art of manufacturing such neckties.

What is claimed is:

1. Mechanism used for sewing and adapted to receive an elongated threaded needle, said mechanism comprising two horizontally aligned series of normally spaced crimping bars, each series being opposite the other series, an elongated extensible and collapsible support on which the bars are mounted so that the bars of each series may be accordingly extended or collapsed, each series of bars being disposed on one side of the longitudinal axis of said support, the bars of one series being swingable over so as to overlie the bars of the other series and being formed so that the bars nest together and become engaged, the bars of each series being respectively formed with complementary recesses which become mutually aligned when the bars are engaged, the aligned recesses forming a needle path when the bars are collapsed and means to transversely adjust the bars on both sides of said longitudinal axis for shifting the respective recesses equally on both sides of said axis.

2. Mechanism according to claim 1 and wherein said support comprises a series of lazy tong links and bars, said crimping bars being mounted on said lazy tong bars and the crimping bars of one series being swingable in a vertical plane relative to said lazy tong bars.

3. Mechanism according to claim 1 and including a series of fabric impaling needles disposed adjacent the longitudinal axis of the support for securing the center of a length of fabric jointly disposed over the bars before the swingable bars are actuated so as to overlie the opposite bars.

4. Mechanism according to claim 3 and including a second series of fabric impaling needles on some of the bars of each series and disposed laterally outwardly of the recesses thereof.

5. Mechanism used for sewing and adapted to receive an elongated threaded needle, said mechanism comprising two horizontally aligned series of normally spaced crimping bars, each series being opposite the other series, an elongated ex-

tensible and collapsible support on which the bars are mounted so that the bars of each series may be accordingly extended or collapsed, each series of bars being disposed on one side of the longitudinal axis of said support, the bars of one series being swingable over so as to overlie the bars of the other series and being formed so that the bars nest together and become engaged, the bars of each series being respectively formed with complementary recesses which become mutually aligned when the bars are engaged, the aligned recesses forming a needle path when the bars are collapsed and a manipulating member connected to substantially all of the swingable series of bars for jointly actuating them into engagement with the opposite bars.

6. Mechanism used for sewing and adapted to receive an elongated threaded needle, said mechanism comprising two horizontally aligned series of normally spaced crimping bars, each series being opposite the other series, an elongated extensible and collapsible support on which the bars are mounted so that the bars of each series may be accordingly extended or collapsed, each series of bars being disposed on one side of the longitudinal axis of said support, the bars of one series being swingable over so as to overlie the bars of the other series and being formed so that the bars nest together and become engaged, the bars of each series being respectively formed with complementary recesses which become mutually aligned when the bars are engaged, the aligned recesses forming a needle path when the bars are collapsed and a manipulating member connected to the central bars of the swingable series of bars while being free of the end bars thereof whereby said end bars may be swung independently of the remaining bars.

7. Mechanism used for sewing and adapted to receive an elongated threaded needle, said mechanism comprising two horizontally aligned series of normally spaced crimping bars, each series being opposite the other series, an elongated extensible and collapsible support on which the bars are mounted so that the bars of each series may be accordingly extended or collapsed, each series of bars being disposed on one side of the longitudinal axis of said support, the bars of one series being swingable over so as to overlie the bars of the other series and being formed so that the bars nest together and become engaged, the bars of each series being respectively formed with complementary recesses which become mutually aligned when the bars are engaged, the aligned recesses forming a needle path and means to transversely adjust the bars on both sides of said longitudinal axis for shifting the respective recesses equally on both sides of said axis.

8. Mechanism used for sewing and adapted to receive an elongated threaded needle, said mechanism comprising two horizontally aligned series of normally spaced crimping bars, each series being opposite the other series, an elongated extensible and collapsible support on which the bars are mounted so that the bars of each series may be accordingly extended or collapsed, each series of bars being disposed on one side of the longitudinal axis of said support, the bars of one series being swingable over so as to overlie the bars of the other series and being formed so that the bars nest together and become engaged, the bars of each series being respectively formed with complementary recesses which become mutually aligned when the bars are engaged, the aligned recesses forming a needle path when

the bars are collapsed, the swingable series of bars being substantially interconnected whereby they may be jointly actuated for interengagement with the opposite bars.

9. Sewing mechanism adapted to receive a threaded needle comprising two horizontally aligned series of elongated bars, means to maintain the bars of each series normally spaced from each other and each series being opposite the other series, each bar of one series being pivoted at one end and adapted to swing over and engage a bar of the other series for clamping fabric deposited over one of said series of bars, and said means to maintain the bars spaced from each other being adjustable so as to reduce the spacing between such bars so as to bring them bodily together and crimp fabric, the bars of each series being respectively formed with complementary recesses which become mutually aligned when the bars are engaged, the recesses of the bars of said one series being formed substantially centrally of their lengths, said reduction of spacing bringing the respective recesses of both series of bars closer together, the aligned recesses forming a needle path.

10. Sewing mechanism according to claim 9 and wherein one of said series of bars is triangularly shaped with the apex upwardly directed, the recesses thereof formed in said apex, the other series of bars being V-shaped, the recesses thereof being formed at the upper ends of the arms of the V.

11. Sewing mechanism according to claim 10 and wherein each bar of one series is hingedly connected to one bar of the other series.

12. Sewing mechanism adapted to receive a threaded needle comprising two horizontally aligned series of bars, means to maintain the bars of each series normally spaced from each other, each series being opposite the other series, each bar of one series being adapted to swing over and engage a bar of the other series for clamping fabric deposited over one of said series of bars, and said means to maintain the bars spaced from each other being adjustable so as to reduce such spacing between the bars so as to crimp the fabric, the bars of each series being respectively formed with complementary recesses which become mutually aligned when the bars are engaged, said reduction of spacing bringing the respective recesses closer together, the aligned recesses forming a needle path, said means to reduce the spacing between the bars comprising a lazy tong mechanism over and to which both series of bars are connected.

13. Sewing mechanism adapted to receive a threaded needle comprising two horizontally aligned series of bars, means to maintain the bars of each series normally spaced from each other, each series being opposite the other series, each bar of one series being adapted to swing over and engage a bar of the other series for clamping fabric deposited over one of said series of bars, and means to reduce the spacing be-

tween the bars so as to crimp the fabric, the bars of each series being respectively formed with complementary recesses which become mutually aligned when the bars are engaged, said reduction of spacing bringing the respective recesses closer together, the aligned recesses forming a needle path, said means to maintain the bars spaced and said space reducing means jointly comprising a series of collapsible links so that

10 the movement of said links is transmitted to one series of bars, and the other series of bars being swingable in a vertical plane relative to said collapsible links, each of said series of bars being hingedly connected to a bar of the other series.

15 14. Sewing mechanism adapted to receive a threaded needle comprising two horizontally aligned series of bars, each series being opposite the other series, each bar of one series being adapted to swing over and engage a bar of the other series for clamping fabric deposited over said bars, and fabric impaling members disposed between the respective series of bars so as to retain fabric in position as the bars of one series are swung over to engage the bars of the other series, the bars of each series being respectively formed with complementary recesses which become mutually aligned when the bars are engaged, the aligned recesses forming a needle guide path, said fabric impaling members comprising 20 needles each needle having an enlargement below its point for anchoring the fabric.

15 15. Sewing mechanism adapted to receive a threaded needle comprising two horizontally aligned series of normally spaced bars, each series being opposite the other series, each bar of one series being pivoted at one end and being adapted to swing over and engage a bar of the other series for clamping fabric deposited over one of said series of bars, means to reduce the spacing between the bars so as to crimp the fabric, the bars of each series being respectively formed with complementary recesses which become mutually aligned when the bars are engaged, said reduction of spacing bringing the respective recesses closer together, the aligned recesses forming a needle path, and fabric impaling means formed on said bars and laterally outwardly of the recesses thereof, said fabric impaling means comprising a needle on some of said bars of one series and an opening for receiving said needle on an opposite bar of the other series, said needle entering said opening when the bars are engaged.
